MAGNETIC TAPE UNIT

Thomas S. Kavanagh, Richard H. Ralston, Ronald R. Campbell, Jesse I. Aweida, and Regomar A. Thurmer, Boulder, Colo., assignors to Storage Technology Corporation, Boulder, Colo.

Filed July 8, 1970, Ser. N. 23,860

Term of patent 14 years

Int. Cl. D14—02

U.S. Cl. D26—5

FIG. 1 is a perspective view showing the front of the magnetic tape unit;

FIG. 2 is a side view; and

FIG. 3 is a top view.

The side not shown is like the side shown while the back is conventional.

Our new, original and ornamental design is characterized by an exposed recess on the front of the unit near the bottom of the unit which receives vertically extending tape columns, a tape storage pocket on the front of the unit between the tape columns and one side of the unit, and a control panel at the top of and substantially

coextensive with the overall width of the unit, all as best illustrated in FIG. 1.

We claim:

The ornamental design for a magnetic tape unit, substantially as shown and described.
